(57) **CLAIM**

The ornamental design for a miniature and reusable sauce bottle with keychain, as shown.

DESCRIPTION

FIG. 1 is a first perspective view of a miniature and reusable sauce bottle with keychain.

FIG. 2 is a second perspective view thereof.

FIG. 3 is a front view thereof.

FIG. 4 is a back view thereof.

FIG. 5 is a left side view thereof.

FIG. 6 is a right side view thereof.

FIG. 7 is a top view thereof.

FIG. 8 is a bottom view thereof; and,

FIG. 9 is an exploded perspective view thereof.

The dot-dash broken lines used in the exploded view represent unclaimed subject matter and form no part of the claimed design.

1 Claim, 9 Drawing Sheets
